UNITED STATES PATENT OFFICE.

VICTOR LOUGHEED, OF SAN FRANCISCO, CALIFORNIA.

LID OR CLOSURE FOR RECEPTACLES.

1,373,437.

Specification of Letters Patent.

Patented Apr. 5, 1921.

Application filed August 21, 1919. Serial No. 318,877.

To all whom it may concern:

Be it known that I, VICTOR LOUGHEED, a citizen of the United States, residing at San Francisco, in the county of San Francisco and State of California, have invented certain new and useful Improvements in Lids or Closures for Receptacles, of which the following is a specification.

This invention relates to closures, and 10 while intended primarily for embodiment in the lid or cover for a receptacle, for example, a lubricating cup or the like, it will be obvious that it is applicable to many forms of receptacles, housings, or the like, 15 where it is desirable to have a movable closure.

The object of the invention is to provide 20 a hingeless receptacle cover which, while greatly simplified in construction by the omission of hinging connections, pintles, or other mechanism liable to become impaired, although, if desired, otherwise inseparably attached to the receptacle, will remain in either open or closed position until intentionally displaced. Accordingly, the primary feature of the invention consists in providing a hingeless cover, which, while adapted to lie in closing position upon the receptacle, is provided with a saddle, preferably upon its inner side, which is constructed to embrace a wall of the receptacle, and which, when the cover is tilted to open position, will embrace the inner and outer sides of a wall of the receptacle and resist return of the cover to closing position until it is intentionally released from its hold upon the wall. A further feature of the invention consists in connecting the cover with the receptacle through resilient means which tends to draw the cover to the receptacle, and thus not only holds the cover in closed position but also holds it in gripping position upon the wall of the receptacle when the cover is open. Still another feature of the invention consists in developing the embracing saddle upon the cover through the medium of an inward projection on the cover, preferably centrally located thereon, which, when the cover is tilted outwardly and while the cover engages the outside of a wall of the receptacle, will rest upon said wall; also a fulcrum

member upon the inner side of the cover offset from the supporting projection sufficiently to bear against the inner side of the 55 wall when the cover is supported in tilting position and resisting the tendency of the cover to swing from tilted position to closing position under the closing influence of gravity or its resilient connection with the 60 receptacle, and thus holding the cover open until it is intentionally displaced from its wall-embracing position and permitted to assume closing position.

Another object is to adapt the cover to 65 function as above described when opened in different directions; to which end, a further feature of the invention consists in constructing the support in the form of a short axial projection with the fulcruming member 70 symmetrically extended in different radial directions therefrom, as, for instance, by making it in the form of a polygonal or circular disk concentric with the support, thereby developing a continuing annular 75 edge embracing saddle between the disk and the cover.

Another object is to adapt the fulcruming member to limit the opening of the cover; to which end said fulcruming member is connected with the support through the medium of an inclined surface through which it bears against the inner wall of the receptacle, as, for instance, by making the fulcruming member in the form of a pyramid 85 or cone in those embodiments of the invention in which the cover is designed for opening in different directions; the effect of this feature being to resist further outward turning movement after the cover has come 90 into bearing on the exterior wall of the receptacle.

In all forms of the invention it is desirable to have a closing influence which tends to hold the cover upon the receptacle, this 95 being in the form of a tension spring suitably anchored to the receptacle and attached to the cover in the line of its supporting projection when the cover is of light construction, or being accomplished by gravity 100 alone when the nature of the receptacle is such that the cover can be made with considerable weight.

In the accompanying drawings the inven-

tion is illustrated as applied to a lubricant receptacle, but it is to be understood that this use is merely illustrative. In said drawings—

5 Figure 1 is a vertical axial section of a lubricant cup with the cover in closed position.

Fig. 2 is a view of the same with the cover open.

10 Fig. 3 is a plan view of the inner side of the cover shown in Fig. 1.

Figs. 4 and 5 are views corresponding to Figs. 1 and 2 but showing a modified construction of cover, and also a different 15 anchorage for the inner end of the closing spring; and

Figs. 6 and 7 suggest polygonal forms of receptacle and cover to which the invention is applicable.

20 1 represents a receptacle or housing which may be of any construction or designed for any purpose, for instance, a grease or oil cup, which may be attached through a threaded shank 2 to a machine part. To 25 close the receptacle 1 a cover 3 is provided which is adapted to be held thereon either by gravity or through the medium of a spring 4 anchored at some suitable point, such, for instance, as through the loop 5 at 30 the bottom of the receptacle. The cover 3 may be tilted in opposition to the spring 4 to gain access to the interior of the receptacle 1, as, for instance, for recharging it with oil or grease; and in order that it may be supported in open position upon the edge of the receptacle 1, it is provided with a support 6, preferably in the form of an axial stud or projection, and a fulcruming member 7, which, when the cover is tilted to 35 bring its support 6 into bearing upon the edge of the receptacle, will come into bearing against the inner wall of the receptacle, as shown in Fig. 2, and so determine the direction of the inward moment developed by 40 the spring 4 that it will be resisted by the bearing of the cover 2 against the edge of the receptacle, and the cover will accordingly remain in open position until positively displaced by pressure at a decided 45 angle to the direction of the spring's influence, namely, by substantial lateral pressure upon the upper side of the open cover. The fulcrum 7, support 6, and cover 3 together develop a wall-embracing saddle 50 which resists tilting of the cover after it has been seated in tilted position upon the wall. The form of this saddle is preferably such that it limits the outward tilting or opening movement of the cover while resisting inward tilting or closing movement. By 55 continuing the fulcrum member 7 symmetrically around the support 6, the cover is adapted to function as described when opened in any direction. If the fulcrum member 7 is so developed as to pro-

vide adjacent the support 6 a bearing which engages the supporting edge of the receptacle in a direction to limit the outward tilting movement of the cover, the fulcrum member will serve to limit the 70 opening of the cover as well as resist its closing moment. This is conveniently accomplished by providing an inclined surface ^{7a} on the fulcrum member 7; or if the fulcrum member be symmetrically formed 75 around the support 6, it may be accomplished by making the fulcrum member in the form of a cone, and the angle of the cone may be selected at will to determine the tilting angle of the cover.

80 The cover may be provided with a marginal flange 8, as suggested in Figs. 1, 2, 3, 6, and 7, which will serve to prevent lateral displacement of the cover upon the receptacle, and which, as suggested in Fig. 2, develops a fulcruming bearing at ^{8a} in the function of limiting the outward tilting movement. But as suggested in Figs. 4 and 85 5, the cover may be made without the flange 8, the fulcrum member 7 being made of sufficient diameter to center the cover upon the receptacle, and the outer edge of the receptacle being beveled so as to establish a firm bearing and resist outward tilting, as suggested in Fig. 5. The spring may also be 90 anchored otherwise than at the bottom of the receptacle, as, for instance, through the medium of a diametric bar ^{5a} (Figs. 4 and 5).

95 As suggested in Figs. 6 and 7, the cover need not be circular in form, but may be made polygonal, for example, square (Fig. 6) or hexagonal (Fig. 7).

The foregoing suggestions will be sufficient to illustrate the application of the present invention.

105 I claim:

1. A hingeless cover for receptacles having a support through which it is adapted to rest upon the edge of the receptacle to which it is applied, and a fulcruming member offset from said support and adapted to bear against the inner wall of the receptacle to resist turning moment developed by closing influence.

110 2. A hingeless cover for receptacles having a fulcruming member on the inner side of the cover, and a support located between the fulcruming member and the cover and adapted to receive the edge of the receptacle when presented between the fulcruming 115 member and the cover.

3. In a hingeless closure for receptacles, a cover, and a fulcruming member spaced therefrom adapted to receive the edge of the receptacle between them and resist displacement of the cover laterally, and a support extending between the fulcruming member and the cover adapted to rest upon the edge of the receptacle.

120 4. A hingeless closure for receptacles com-

130

- prising a cover, a projection from the inner surface of the cover adapted to support the cover upon the edge of the receptacle, and a fulcruming member adapted to bear against the inner wall of the receptacle at a point offset from the support, whereby it resists closing movement, and at a point adjacent the support whereby it limits outward tipping movement of the cover.
- 5 5. In a hingeless closure for receptacles, a cover, an axial extension from the inner surface of the cover adapted to support the cover upon the receptacle, and an annular fulcruming member symmetrically distributed around said support.
- 10 6. A closure for receptacles comprising a cover, a projection from the inner surface of the cover adapted to support the cover upon the edge of the receptacle, and a fulcruming member adapted to bear against the inner wall of the receptacle at a point offset from the support, whereby it resists closing movement, and at a point adjacent the support, whereby it limits outward tipping movement of the cover; said fulcruming member being symmetrically extended on a plurality of sides of the support.
- 15 7. In a closure for receptacles, a cover, an axial extension from the inner surface of the cover adapted to support the cover upon the receptacle, and a fulcruming member symmetrically distributed around said support; said fulcruming member being in the form of a polygon or cone.
- 20 8. The combination of a receptacle, a hingeless cover therefor, a fulcrum member, a support connecting the fulcrum member to the inner side of the cover, and a spring connecting the cover with the receptacle and located to draw the cover to closing position 40 upon the receptacle.
- 25 9. In a closure for receptacles, a hingeless cover, an axial extension from the inner surface of the cover adapted to support the cover upon the receptacle, and an annular 45 fulcruming member symmetrically distributed around said support; said cover having a spring tending to hold it in position.
- 30 10. A closure for receptacles comprising a hingeless cover, a projection from the inner surface of the cover adapted to support the cover upon the edge of the receptacle, and a fulcruming member adapted to bear against the inner wall of the receptacle at a point offset from the support, whereby it 50 resists closing movement, and at a point adjacent the support, whereby it limits outward tipping movement of the cover; said fulcruming member being symmetrically extended on a plurality of sides of the support; and said cover having a spring tending to hold it in position.
- 35 11. In combination with a receptacle, a hingeless cover therefor having a saddle constructed to receive and embrace a wall 65 of the receptacle when the cover is tilted from its closing position thereon.
- 40 12. In combination with a receptacle, a cover adapted to assume closing relation thereto and having a saddle constructed to 70 receive and embrace a side wall of the receptacle when the cover is tilted from closing position and thereby hold the cover in open position.
- 45 Signed at Chicago, Illinois, this 25th day 75 of July, 1919.

VICTOR LOUGHEED.
